UNITED STATES PATENT OFFICE.

EDWARD E. ROBERTS, OF WHEELING, WEST VIRGINIA, ASSIGNOR TO STEEL FIRE-PROOFING COMPANY, A CORPORATION OF WEST VIRGINIA.

PUNCHING-DIES.

1,081,517.

Specification of Letters Patent. Patented Dec. 16, 1913.

Application filed March 1, 1911. Serial No. 611,639.

To all whom it may concern:

Be it known that I, EDWARD E. ROBERTS, a resident of Wheeling, in the county of Ohio and State of West Virginia, have invented a new and useful Improvement in Punching-Dies, of which the following is a specification.

This invention relates to slitting and punching dies, and more particularly to dies for slitting sheet metal preparatory to expanding the same.

The object of the invention is to improve dies of this character in details hereinafter described and claimed, and particularly to provide simple and efficient means for stripping the slit sheets from the cutters.

The invention comprises the construction and arrangement of parts hereinafter described and claimed.

20 In the accompanying drawings Figure 1 is in part a side elevation and in part a vertical longitudinal section on the line 1—1, Fig. 2, showing dies constructed according to my invention; Fig. 2 is a plan view of 25 one of the dies with the stripper bars omitted; and Fig. 3 is a transverse section on the line 3—3, Fig. 2.

The improved dies are preferably used in oppositely arranged pairs; that is a lower 30 die 1 and an upper die 2. Each die comprises a suitable holder or die block 3 arranged to be suitably connected to any suitable mechanism for imparting to the dies the necessary movements of proximation 35 and separation. The holder or die block is provided with one or more recesses 4 for receiving the cutters 5, the latter being in the form of flat plates provided at their protruding ends with cutting edges. The 40 cutters of the two series have their cutting edges out of alinement, that is the cutting edges of one series being midway between the cutting edges of adjacent cutters on the other series, as shown in Fig. 2, so as to

45 provide the sheet with rows of slits, with the slits of adjacent rows overlapping or alternating one with the other, so that when expanded a diamond mesh is formed. These plates are placed in the recesses one against 50 the other, or if desired with suitable spacers or shims therebetween, and are held in position in the recesses by being clamped tightly one against the other by suitable means, such as screws 6 working in tapped holes 55 in the end portion of the holder or die block

and at their inner ends bearing against the endmost cutters or preferably against following blocks 7 in the recesses 4. The outer ends of the screws are square or otherwise shaped for the attachment of a wrench or key for turning the screws. The end of the holder or die block is provided with suitable recesses 9 into which the outer ends of the screws 6 project. The holders or die blocks are also provided with vertical bushings 10 for receiving suitable guide pins for guiding the holders in their reciprocating movements in order to guide the edges of the cutters into shearing relation.

Suitable strippers are provided for stripping the slit sheets from the cutters, and preferably a stripper bar is provided at each side of each row of cutters. As shown the holder is provided with three longitudinal recesses 11, one on each side of the holder 75 and one between the two rows of cutters. In the two outside recesses are located stripper bars 12 which extend fairly close to the ends of the holder, and between the two rows of cutters is the center stripper bar 13 which 80 is shorter on account of the bushings 10. Each stripper is substantially the length of its recess and is guided in its up and down movement by means of a plurality of pins 14 reciprocating in holes formed from the 85 holder and having one end riveted or otherwise suitably attached to the stripper bar and having secured to their outer ends suitable adjustable collars 15 moving in recesses 16 in the outer faces of the holders or die 90 blocks. As shown these collars are in the form of nuts threaded onto the pins and provided with suitable recesses 17 for receiving a spanner wrench or other tool for rotating the same. The stripper bars are pressed outwardly, that is to strip the slit sheet from the cutters, by means of springs 18 surrounding the pins 14 and seated in pockets 19 in the outer faces of the holders or die 95 blocks. These springs yield when the dies come together, permitting the stripper bars to move down into the recesses 11 in the holders or die blocks, but as soon as the dies separate these springs lift the stripper bars 100 out of their recesses and strip the sheet 105 from the cutters. The nuts or collars 15 limit the extent of such lifting movement of the stripper bars.

The dies described are of simple construction, the cutters are securely held in the 110

holders or die blocks, and effective means are provided for stripping the slit sheet from the cutters.

What I claim is:

5. 1. In a sheet-metal slitting machine, the combination of upper and lower die members movable with reference to each other and each comprising, a holder, a plurality of cutters, a stripper bar seated in the 10 holder, and springs for moving said stripper bar out of its recess in said holder, the cutters on the respective die members being arranged to shear parallel closed slits in a sheet, and the stripper bars in said die members being disposed opposite to each other and arranged upon movement of said dies 15 to hold said sheet while being slitted and then strip the same from said cutters.
2. In a sheet-metal slitting machine, the 20 combination of upper and lower die members movable with reference to each other and each comprising, a holder, a row of parallel knife-edged cutters, a movable stripper bar seated on each side of said row of 25 cutters, springs for moving said stripper bars out of said holders, the cutters on the respective die members being arranged in coöperative relation to each other and adapted to shear parallel closed slits in a sheet,

and the stripper bars in said die members 30 being disposed in pairs opposite to each other and arranged upon movement of said dies to hold said sheet while being slitted and to then strip the same from said cutters.

3. In a sheet-metal slitting machine, the 35 combination of upper and lower die members movable with reference to each other and each comprising, a holder, two sets of knife-edged cutters, said cutters being disposed parallel to and in row with each other, 40 stripper bars between and on either side of said sets of cutters and movable in said holder, springs for moving said stripper bars out of said holders, the cutters on the respective die members being arranged in 45 coöperative relation to each other and arranged to shear parallel closed slits in a sheet, and the stripper bars in said die members being disposed opposite to each other and arranged upon movement of said dies 50 to hold said sheet while being slitted and strip the same from said cutters.

In testimony whereof, I have hereunto set my hand.

EDWARD E. ROBERTS.
